UNITED STATES PATENT OFFICE.

HENRY W. PETERS, OF BOSTON, MASSACHUSETTS.

SAFETY-JOINT.

1,148,855.

Specification of Letters Patent.

Patented Aug. 3, 1915.

Application filed August 20, 1914. Serial No. 857,739.

To all whom it may concern:

Be it known that I, HENRY W. PETERS, a citizen of the United States, residing at Boston, in the county of Suffolk and State of Massachusetts, have invented a new and useful Safety-Joint, of which the following is a specification.

The present invention appertains to a safety joint for jewelry, and aims to provide a novel and improved hinge joint for connecting the pins or tongues to badges, buttons, or other articles of jewelry, whereby there will be no liability for the pin or tongue and article or body becoming detached and lost.

As a more specific object, the present invention contemplates the provision of a hinge joint embodying a hinge pin assembled with the hinge ears in a peculiar manner, to lock the hinge pin against removal or withdrawal, to hold the ears against separation, and to provide an efficient bearing for the eye of the pin or tongue.

It is also within the scope of the invention, to provide a safety joint of the character indicated, which will be comparatively simple and inexpensive in construction, which will enable the component parts to be readily assembled, and which will be practical, convenient and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiments in the accompanying drawing, wherein:

Figure 1 is a perspective view of an article of jewelry embodying the improved hinge joint. Fig. 2 is an enlarged sectional view of the joint prior to the squeezing or compressing of the hinge pin. Fig. 3 is a view similar to Fig. 2, illustrating the hinge pin in compressed and assembled position. Fig. 4 is a view similar to Fig. 3, illustrating a modification, the hinge pin being illustrated in its original position in dotted lines.

In carrying out the present invention, there is provided a hinge body or member

1 which is soldered or otherwise secured to the badge, button or other article of jewelry 2 as usual, and which is provided with a pair of spaced parallel hinge ears 3. The hinge body or member 1 may be forged or otherwise formed of suitable metal, and the pin or tongue 4 has its eye 5 disposed snugly between the ears 3, while its free end is engageable with the catch or hook 6 secured to the article 2, it being understood that safety catches such as disclosed in my co-pending application Serial No. 780,299, and Patent No. 1,112,317, may be employed if desired.

Coming to the salient and cardinal features of the present invention, the ears 3 are provided with central apertures alining with the aperture of the eye 5, and the ears 3 are provided with annular grooves or rabbets 7 adjacent their inner faces and surrounding the inner ends of the apertures of the ears, while the apertures or bores of the ears 3 are flared or tapered as at 8 from the grooves 7 to the outer faces or sides of the ears. The outer sides or faces of the ears 3 are preferably rounded, so as to thicken the ears, and to elongate the apertures or bores of the ears correspondingly to provide a firm hold for the hinge pin 9. The tapered portions 8 of the apertures or bores of the ears 3 extend inwardly, that is, the largest ends of the tapered portions 8 are disposed outermost.

The hinge pin 9 in its original condition, is straight and of uniform diameter throughout as seen in Fig. 2, and is formed of soft or malleable metal. The hinge pin 9 in its original condition is slightly longer than the aggregate lengths of the apertures of the ears 3 and eye 5, whereby when the hinge pin 9 is inserted through the said apertures, the ends of the hinge pin will protrude as seen in Fig. 2.

In assembling the several parts, the eye 5 of the pin or tongue 4 is first inserted between the ears 3, and the hinge pin 9 is then inserted through the ears 3 and eye 5 as seen in Fig. 2. The hinge pin 9 is then squeezed or compressed longitudinally or axially, so as to shorten the same, and to compress the same snugly or tightly into the grooves or rabbets 7 and the tapered portions 8 of the apertures of the ears 3. It is to be noted that due to the provision of the grooves 7 and tapered portions 8, there is provided between each groove and

tapered portion, a sharp annular ridge, so that when the pin is expanded within the ears 3 and eye 5, the said sharp ridges will serve to cut the pin in order that it will properly expand within the grooves 7. It is also to be understood that the device is illustrated on an enlarged scale in the drawing, and that the spaces between the ears 3 and eye 5 are exaggerated, since in practice 10 the eye 5 would fit snugly between the ears 3 to avoid the possibility of the hinge pin expanding into the space between the ears and eye. It is possible that the hinge pin might expand within the eye 5, but this 15 would not impair the swinging movement of the tongue 4, but on the other hand, would cause the tongue to swing without any loose play. If the tongue should work or swing hard after the hinge pin has been 20 expanded within the ears and eye, the tongue may be oscillated to provide smooth bearing surfaces between the hinge pin and eye, and the bearing surfaces therebetween may be lubricated if necessary. Thus, the 25 hinge pin 9 being expanded within the ears 3 as indicated, will not only lock the hinge pin securely in engagement with the ears, but will lock the ears in place, so that they cannot separate or spread. Furthermore, 30 the annular ribs or beads 10 of the hinge pin which are expanded into the grooves or rabbets 7, will provide bearings for the sides of the eye 5, to hold the eye in place, to enable the same to rotate in the true manner. The annular ribs 10 will also reduce 35 the wear between the eye 5 and the ears 3 and the expanded tapered portions 11 of the hinge pin 9 within the tapered portions 8 of the apertures or bores of the ears 3, will 40 firmly hold the ears and hinge pin in proper assembled relation. The ends of the hinge pin 9 are finally filed or trimmed flush with the outer faces of the ears 3.

The present joint will prevent the pin or 45 tongue 4 from becoming loosened from the hinge member or body 1 which is secured to the article 2, and as a result, the liability for

the article 2 being lost will be reduced to a minimum.

In the variation illustrated in Fig. 4, the 50 hinge body or member 1' has the ears 3' between which the eye 5' of the pin or tongue is disposed, and the apertures or bores of the ears 3' are provided with annular grooves or rabbets 7' around their inner or 55 adjacent ends, and the said apertures or bores are tapered outwardly, as at 8', from the grooves or rabbets 7' to the outer faces of the ears. The soft metal hinge pin 9' is inserted through the apertures of the ears 60 3' and eye 5', and is squeezed or compressed longitudinally so that its central or intermediate portion is expanded within the apertures of the ears and eye, and to provide the annular ribs or beads 10' fitting within 65 the grooves 7' and the tapered portions 11' fitting within the tapered portions 8' of the apertures or bores of the ears.

The variation illustrated in Fig. 4 has the same general functions as the form of the 70 invention illustrated in Figs. 2 and 3.

Having thus described the invention, what is claimed as new is:—

A safety hinge joint embodying a pair of spaced apertured ears, an eye disposed between the ears, each ear having an annular groove surrounding the inner end of its aperture and having its aperture tapered from the said groove to the outer face of the ear to provide a sharp annular ridge between the groove and tapered portion, and a soft metallic hinge pin disposed within the apertures of the ears and eye and having expanded portions fitting tightly within the 80 said grooves and tapered portions of the 85 apertures of the ears.

In testimony that I claim the foregoing as my own, I have hereto affixed my signature in the presence of two witnesses.

HENRY W. PETERS.
